BALING PRESS

Ami L. Young, Compton, Calif.

Application December 3, 1956, Serial No. 625,927

5 Claims. (Cl. 100—215)

This invention relates to an improved baling press, and has for one of its principal objects the provision of a device of the class described which will be useful in the art of compressing practically any materials into a bale, bundle or package in a substantially automatic mechanical or other means.

Another object of the invention is the provision of a compressing mechanism for baling various materials, particularly refuse, paper, or the like in a simple automatic manner, and which will produce a neat, easily disposed of, unit, which can be of any desired size depending upon requirements, varying from the needs of the small residence user to the large factory user.

A further object of the invention is to provide a baling press or the like, particularly for trash or refuse, wherein large quantities of such material will be drastically reduced in volume for easier and faster handling.

Yet another object of the invention is the provision of a baling mechanism, wherein raw trash and other refuse would be handled in a single operation, namely when it is placed in the apparatus of this invention.

Another and still further important object of the invention is to enable disposal trucks to handle a great deal more of such refuse in a highly efficient and better organized manner, thereby reducing the number of trash pick-ups in any area.

Other and further important objects of the invention will be apparent from the disclosures in the accompanying drawings and following specification.

The invention, in a preferred form, is illustrated in the drawings and hereinafter more fully described.

In the drawings:

Figure 1 is an elevation of the improved baling press of this invention, partly in section and parts being broken away.

Figure 2 is a horizontal section taken on the plane of the line 2—2 of Figure 1, looking downwardly.

Figure 3 is a vertical section on the line 3—3 of Figure 1, looking in the direction indicated by the arrows.

Figure 4 is a partial section, on the broken line 4—4 of Figure 1, looking in the direction indicated.

Figure 5 is an enlarged fragmentary section on the broken line 5—5 of Figure 4.

Figure 6 is also an enlarged fragmentary section taken on the plane of the line 6—6 of Figure 1, looking in the direction indicated by the arrows.

Figure 7 is a perspective view, showing a portion of the main frame of the improved baling press of this invention.

Figure 8 is a perspective, on a reduced scale, of one of the closure elements which comprise an important feature of the baling press of this invention.

As shown in the drawings:

The reference numeral 10 indicates the machine generally having a main frame 11. This main frame 11 is supported upon a base member 12 and includes end walls 13 and longitudinal tie members 14 at the top of

2

the main frame 11. Additional longitudinal tie members 15 are provided at the middle portion of the main frame 11 and uprights or columns 16 extend throughout the height of the entire apparatus. These columns are connected by a head member 17 at the top thereof; 5 and doors 18 form the two side walls of the lower chamber for final compression of whatever material which is placed in the apparatus. These doors 18 include reinforcing ribs 18a and are mounted on hinges 19, all as best shown in Figure 3. Lugs 20 are provided for shear pins 21 on the doors 18, and additional lugs 22, which cooperate with the lugs 20, are on the base 12 (Figure 6).

The doors 18 are provided with notches 23 in order to clear the lugs 20, all as best shown in Figure 1, and hooks 24 are provided for holding the doors 18 in open position, see the dotted lines in Figure 3.

The material introduced into the machine is compressed by a ram 25 which is adapted to move from the full line position shown in Figure 3 to the dotted line position illustrated in the same figure. The ram 25 is provided with a ram rod 26 which is connected to a piston 27 (Figure 1) operating on a cylinder 28 (Figures 2 and 3) which cylinder is supported by a mounting plate 29 (Figures 1 and 3).

20 The piston 27, connected by the ram rod 26 to the ram 25, is hydraulically operated from a conventional power source 30 (Figure 1) which includes a motor 30a, a pump 30b, a pressure relief valve 30c, a three position valve 30d, a reservoir 30e and conduits 30f.

25 It will be understood that the gates 18 are opened to remove compressed material from the device after the ram 25 has operated, and when the ram 25 is in its upper-most position, as shown in Figure 3, trash, rubbish or any other material to be compressed can be introduced into the space below the ram 25 through gates 31 which are adapted for up and down vertical movement in slots 32 in the walls 15. The walls 13 are also provided with slots, as shown by the reference numerals 33 (Figure 7) and additional slots 34 are provided in the walls 14 for reception of the gates 31 when in their upper position.

30 Each of the gates 31 is provided with projections 35 (Figure 8), to which cables 36 may be attached (Figures 1 and 3). The cables 36 operate over pulleys or sheaves 37 mounted on shafts 38, which shafts are supported on bearing brackets 39 (Figure 2). Additional sheaves or pulleys 40 are fixed on shafts 41 mounted in bearing brackets 42 (Figures 2 and 3).

35 Cables 44 have their ends attached to the peripheries of the sheaves 43 and bell cranks 45, pivoted at 46 have their outer ends connected to the cables 44.

40 Lugs 47 on the cylinder 28 (Figures 4 and 5) support the shafts 46 and rollers 48 mounted on pins 49 in the bell cranks 45 operate against cam elements 50 which are positioned on the ram 25, all as best shown in Figures 1 to 5 inclusive.

45 The reference numeral 50a indicates a relief on a cam 50 (Figure 5), and this is defined by an incline 50b and includes a dwell or holding surface 50c.

50 Springs 51 are attached to the lower ends of the gates 31, as shown in Figure 1, and sloping sides 52 mounted on hinges 53 are provided to form part of the hopper construction.

55 This hopper construction also includes end cheek plates 54 (Figures 2 and 3) provided with arcuate slots 54a. Angle brackets 55 are fitted onto the hopper sides 52 and these include studs 55a which pass through the slots 54a and winged nuts 56 are fitted onto the studs 55a, 70 whereby the hinged hopper sides 52 allow material placed thereon to automatically slide under the ram. The sides

can be adjustably fixed in position with respect to the cheek plates 54.

As the ram 25 and its connections, including the cams 50, moves up and down, the rollers 48 on the bell-cranks will operate against the faces 50a and 50c of the cams 50, thereby moving the outer ends of the bell-cranks 45 in such a fashion that the cables 44 will move the sheaves 40—43 and the attached cables 36 over the pulleys 37 so as to accordingly and simultaneously move the gates 31 in a reverse vertical operation. In other words, when the ram 25 is moving downwardly, the gates 31 are moving upwardly and vice versa. This will automatically confine the material to be compressed between the gates 31 during the compressing and baling operation while at the same time allowing ready access to the interior for placing material in the press when the ram 25 is in its uppermost position.

Grooves 57 are provided in the top surface of the base 12, all as best shown in Figures 1 and 3, and these grooves are for the insertion of baling wires or strips which can be inserted therein prior to charging of the press. In this manner a suitable bale may readily be formed after the material in the press has been compressed into the desired minimum space, and this wired or strapped bale can then be readily removed from the press through the gates 18.

It will be evident that the apparatus of this invention will provide a simple, convenient, readily operated and practically automatic mechanical device, which will compress all types of such material, including trash, refuse, tin cans and the like into a neat, easily handled unit. It will eliminate the need for incinerators, which contribute to a great degree to the impurity of air, and resultant "smog" in a community or area so affected will be reduced.

The invention will also provide a neat, useful and properly organized method for disposing of refuse, thereby improving the appearance of refuse storage areas around homes, restaurants, schools, factories and other commercial and non-commercial establishments, all of which include at one time or another the necessity of trash disposal.

The apparatus will materially reduce fire hazard and storage space for the refuse will be at a minimum. Considerable time in the disposal operations will also be saved.

The device may be made in practically any size and can be used for baling paper, cotton, excelsior and all sorts of other materials.

I am aware that many changes may be made and numerous details of construction varied throughout a wide range without departing from the principles of this invention; and I, therefore, do not propose limiting the patent hereon otherwise than as necessitated by the prior art.

I claim as my invention:

1. A baling press comprising a main frame having a base, side and end walls, doors forming part of the side walls of the lower portion of the frame, means for locking said doors in closed position, slidable gates forming part of the upper portions of said side walls, said gates being normally biased to a lowered position to provide a material receiving opening through the upper portions of said side walls, a ram, ram-rod and piston for compressing the material in the frame, means for automatically raising the slidable gates when the ram is depressed, hydraulic means for operating the piston, ram-rod and ram, said hydraulic means including a cylinder, a motor, a supply of fluid, conduits and valves, the means for raising the gates in unison with the ram including cables connected at one of their ends to said gates and at their other end to means on the cylinder, sheaves and pulleys mounted on said frame over which said cables are directed and cam elements on the ram adapted to cooperate with the means on the cylinder for controlling the cables in their movement over the pulleys.
2. A device as described in claim 1, wherein said last named means comprises bell cranks which cooperate with the cam element, said bell cranks being connected to the cables and pivoted on the hydraulic cylinder.
3. A device as described in claim 2, wherein the bell cranks include rollers which are adapted to cooperate with the cams on the ram.
4. A device as described in claim 1, wherein the device includes hinged adjustable sides mounted on the upper portion of the frame.
5. A device as described in claim 4, wherein said hinged adjustable sides are adjacent the slidable gates and provide automatic feed means for the material to be placed in the hopper.
